COVER STRUCTURE FOR SUITCASES,
VALISES, AND SIMILAR CARRYING
CASES

Alex Hochner, New York, N. Y.

Application November 29, 1946, Serial No. 712,833

6 Claims. (Cl. 190—41)

1

This invention concerns improvements in or relating to carrying cases, suitcases, valises or similar pieces of luggage.

It is one of the main objects of this invention to provide means assisting in the obtainment of a strong and sturdy frame structure for suitcases and the like whose shape will always be maintained and which is particularly adapted to cooperate with a relatively flexible top wall or cover which will bear against said frame structure for closing purposes.

It is another object of this invention to provide means ensuring maximum filling capacity for suitcases and like pieces of luggage and facilitating retention of the packed garments or clothes in a position in which they do not interfere with the slide fastener means or other closure elements usually employed for closing such carrying cases.

A further object of the present invention is to provide means rendering possible the positioning of one of the rows of the slide fastener means on the surface of the frame ledge and intermediate the opposed ends thereof, whereby a substantially dustproof closure between the frame and the relatively flexible top wall or cover is obtained without sacrificing any of the known advantages of such flexible covers.

A further object of the invention is to provide means enabling ready adjustment of the position of the flexible cover with respect to the frame structure, but permitting the cover nevertheless to give or bulge when additional articles or items are placed in the new valise or suitcase.

Still another object of the invention is to provide means for stiffening or reinforcing that top wall portion of the valise or suitcase with which the flexible cover or complementary top wall part cooperates.

Yet, another object of the present invention is to provide means facilitating packing and disposing of articles within said valise or suitcase and creating therewithin a predetermined space for which the aforesaid frame ledge forms a boundary against which said articles may abut.

With the above and other objects in view, the invention will be hereinafter more particularly described and the combination and arrangement of parts will be shown in the accompanying drawing and pointed out in the claims which form part of the specification.

Reference will now be had to the drawing wherein like numerals of reference designate corresponding parts throughout the several views.

In the drawing:

2

Fig. 1 is a perspective view of a suitcase in closed condition, embodying the invention;

Fig. 2 is a fragmentary view of the suitcase of Fig. 1, partly in open condition;

Fig. 3 is a fragmentary, sectional view taken along line 3—3 of Fig. 1;

Fig. 4 is a sectional view taken along line 4—4 of Fig. 2;

Fig. 5 is a sectional view taken through a corner of a suitcase embodying the invention in a modified form.

Referring now more particularly to the drawing, there is shown in Fig. 1 a suitcase 10 having side walls 11, a bottom wall (not shown) and a top wall or cover 12. The suitcase 10 is conventional but for the cover 12 and its particular attachment about to be described.

As can be seen from Figs. 2 and 3, the top wall 12 of the suitcase 10 extends to a location remote from the edge 13 of the upright side wall 11. Side wall 11 has an inwardly extending ledge 14 which is sufficiently wide to retain within the interior 15 of the suitcase 10 articles 16 placed therein, and also to receive on the top 17 of the ledge 14 the edge 18 of the flexible cover 12, as well as the closure means in the form of a slide fastener 19.

As seen in Figs. 3 and 4, ledge 14 is provided with a binding 20 which may preferably be made from leather or rubberized material having sufficient strength and elasticity. This binding 20 is fixed along the free edge 21 of the ledge 14 and embraces the same to a certain extent. In the present instance, the binding 20 further holds the tape 22 of the lower slide fastener elements 19a and is affixed to the ledge 14 by means of stitches 23. It is well understood that any other attaching means, such as glue or any suitable adhesive may be employed instead of stitches 23.

It is to be observed that the upper wall 20a of the binding 20 is preferably of such height or thickness that between said upper wall 20a and lower slide fastener elements 19a a space 25 is created into which the reinforced end 24 of the flexible cover 12 fits.

This reinforced end 24 has a rim 26 which in closed condition of the cover 12 comes to lie in abutment position with the edge 27 of the binding 20.

As will be seen from Fig. 4, the flexible cover 12 may consist of two layers, an outer layer 28 made of leather or similar strong and pressure-resistant material, and an inner layer 29 of canvas, rubberized material and the like, which may suitably form a lining for the outer layer 28.

Adjacent the end 30 of cover 12 there is inserted between layers 28 and 29 a tape 31 carrying at its free end the upper slide fastener elements 19b. Tape 31 is preferably affixed intermediate said layers 28 and 29 by means of stitches 32. Layer 29 is preferably doubled up or folded over to form the reinforced end 24 which may be thus attached to the layers 28 and 29, as it is well understood.

As may be easily realized from Figs. 3 and 4, cover 12 when being moved down onto the relatively stiff frame or ledge 14 in the direction of arrow A to achieve closing of the suitcase 10, will immediately adjust itself with respect to the space 25 so that the slide fastener elements 19a and 19b may be readily actuated by the slide 33 to close the cover 12 on the suitcase 10.

As can be seen from Fig. 3, reinforced end 24 in closed condition of cover 12 is received within the space 25 and protects the interior 15 of the suitcase 10 against access of dust from the outside through slide fastener 19.

It is well understood that the binding 20 and the reinforced end 24 of layer 29 may also be made of rubber or other pliable and plastic material to bring about a substantially tight engaging fit and meander-shaped connection between the frame-shaped ledge 14 and the cover 12 of the suitcase 10.

It will be seen from the above that although the cover 12 may be tightly closed on ledge 14, the cover is still allowed to bulge or give (indicated in dot-dash line in Fig. 3) to ensure maximum filling capacity for the suitcase or like luggage and to facilitate retention of the packed articles 16 beneath the surface 34 of the ledge 14, whereby the articles are prevented from interfering with the slide fastener means or other closure elements usually employed.

Since the frame-shaped ledge 14 considerably reinforces the top wall 12 of the suitcase 10, a sturdy structure is achieved despite the fact that the complementary part of the top wall 12 which is flexible may give so that the new suitcase combines the advantages of a suitcase with entirely stiff walls and of a suitcase having a flexible wall extending the entire length of the cover.

Fig. 5 shows a similar structure as that illustrated in Fig. 3 with the exception that the outer layer 28a of the cover 12a extends beyond the slide fastener 19 and forms a flap 28b whose end is closed adjacent the edge 13 of the upright side wall 11 by means of snap buttons 35 so that the flexible cover 12a is substantially co-extensive with the upright side wall 11 although ledge 14 is employed for the purposes and advantages hereinabove referred to.

The extension 28b contributes to the aesthetic appearance of the outer shape of the suitcase or similar piece of luggage and further provides between it and the ledge 14 a space 36 in which an umbrella or any other elongated articles may be temporarily housed. This structure, of course, improves further the protection of the valise or suitcase against dust and the like.

Briefly, it may be stated and it can be seen that there has been provided according to this invention a suitcase or valise of the character described which has a substantially rigid body 10 including side walls 11 having an upper margin 13 and a top ledge 14. The top ledge 14, which is U-shaped and defines an opening 14a, extends substantially at right angle to the side walls 11 and is connected to the latter at the upper margin 13 thereof. The inner edge 21 of the ledge 14 is provided with

a binding 20 forming a reinforcement. Between said binding and the top surface of the ledge 14 there is arranged a tape 22 carrying at its free end the lower slide fastener elements 19a. This tape is retained by said binding 20 on top of said ledge and extends a predetermined distance from said binding, whereby a space 25 is obtained between said binding and said lower fastener element 19a. The suitcase further includes a flexible cover 12 which is swingably disposed on said suitcase body and shaped to overlie said opening 14a in closed condition of said suitcase. The cover 12 includes an outer layer 28 and an inner layer 29 forming a lining for said outer layer, the inner layer terminating in a reinforced end 24 adapted to engage at 26 said binding 20 and to fit within said space 25 in closed condition of the suitcase.

A tape 31 carrying upper fastener elements 19b is disposed at and projects beyond said reinforced end 24 of said cover. The upper fastener elements 19b are engageable with said lower fastener elements 19a upon closing of said cover and being spaced from said upright walls 11.

According to a modification of said structure, the outer layer 28a includes an extension flap 28b overlying said binding 20, said reinforced end 24 and said fastener elements 19 and is adapted for engagement with said ledge 14 adjacent said upper margin 13 of said walls. Interfitting formations 35a, 35b formed of snap buttons are, respectively, disposed at said ledge 14 and at said extension flap 28b for effectuating said engagement.

As many possible embodiments may be made of the above invention, and as many changes might be made in the embodiments above set forth, it is to be understood that all matters hereinbefore explained or shown in the accompanying drawing, are to be interpreted as illustrative and not in a limiting sense.

Having thus described the invention, what is claimed as new and desired to be secured by Letters Patent, is:

1. In a suitcase provided with upright walls; a frame-shaped ledge angularly directed from and forming an extension of said upright walls, said frame-shaped ledge terminating in a free edge, said free edge being provided with a binding, said binding including a tape carrying first fastener elements, said first fastener elements being movably positioned on said ledge and substantially intermediate said binding and said upright walls, whereby a space is provided between said binding and said first fastener elements, a cover arranged for position on said ledge, said cover terminating in a reinforced end for location within said space, in closed condition of said suitcase, and a tape fixed above and projecting beyond said reinforced end and carrying second fastener elements, said second fastener elements being complementary to said first fastener elements and facilitating closing of said suitcase.

2. In a suitcase provided with upright walls; a frame-shaped ledge forming an open top and angularly extending from said upright walls, said frame-shaped ledge having a free inner edge, said inner edge being provided with a binding, a tape carrying first fastener elements extending from said binding onto said ledge for position intermediate said binding and said upright walls, whereby a space is provided between said binding and said first fastener elements, a flexible cover for closing said open top of said suitcase, said cover including a lining terminating in a rein-

forced end for position within said space, and a tape fixed above and projecting beyond said reinforced end and carrying second fastener elements, said second fastener elements being complementary to said first fastener elements and facilitating closing of said suitcase.

3. A suitcase and like luggage having upright walls comprising a frame-shaped ledge forming an open top and extending angularly to said upright walls, said ledge terminating in an edge, means reinforcing said edge and extending from the latter on said ledge, a tape carrying first fastener elements attached to said reinforcing means, whereby said first fastener elements come to lie on said ledge and substantially intermediate said reinforcing means and said upright walls to thereby form a space between said means and said first fastener elements, a flexible cover fixed to one of said upright walls and swingable thereabout for closing said open top of said suitcase, said cover including a reinforced rim, said rim being adapted for position within said space, and for engagement with said reinforcing means, whereby a substantially dustproof connection is obtained, and a tape projecting beyond said reinforced rim and carrying second fastener elements, said second fastener elements being complementary to said first fastener elements and facilitating closing of cover on said suitcase.

4. A suitcase and like luggage having substantially rigid upright walls and a flexible cover swingably attached thereto, a top ledge forming a frame, said frame being substantially rigid and extending from said upright walls, said ledge having a reinforced inner edge, a tape carrying first fastener elements and extending from said reinforced edge to a position substantially intermediate said edge and said upright walls, whereby a space is provided between said reinforced edge and said first fastener elements, said flexible cover being adapted for position onto said ledge and terminating short of said upright walls from which said ledge extends, said cover including a lining terminating in a reinforced rim, said rim being adapted for position within said space and for engagement with said reinforced inner edge, and a tape fixed above and projecting beyond said reinforced edge and carrying second fastener elements for engagement with said first fastener elements to close said suitcase.

5. A suitcase or valise of the character described comprising a substantially rigid body including side walls having an upper margin and a top wall, said top wall being provided with a rectangular opening, said opening being defined by a U-shaped ledge extending substantially at right angle to said side walls and being connected to the latter at the upper margin thereof, the inner edge of said ledge being provided with a binding forming a reinforcement of said edge, a tape carrying first fastener elements retained by said binding on the top of said ledge and extending a predetermined distance from said binding, whereby a space is obtained between said binding and said first fastener elements, a

substantially flexible cover swingably disposed on said body and shaped to overlie said opening in closed condition of said suitcase, said cover including an outer layer and an inner layer forming a lining for said outer layer, said inner layer terminating in a reinforced end adapted to engage said binding and to fit within said space in said closed condition, and a tape carrying second fastener elements and disposed at and projecting beyond said reinforced end of said cover, said second fastener elements being engageable with said first fastener elements upon closing of said cover and being spaced from said upright walls.

15 6. A suitcase or valise of the character described comprising a substantially rigid body including side walls having an upper margin and a top wall, said top wall being provided with a rectangular opening, said opening being defined by a U-shaped ledge extending substantially at right angle to said side walls and being connected to the latter at the upper margin thereof, the inner edge of said ledge being provided with a binding forming a reinforcement of said edge, a tape carrying first fastener elements retained by 20 said binding on the top of said ledge and extending a predetermined distance from said binding, whereby a space is obtained between said binding and said first fastener elements, a substantially flexible cover swingably disposed on said body and shaped to overlie said opening in closed condition of said suitcase, said cover including an outer layer and an inner layer forming a lining for said outer layer, said inner layer terminating in a reinforced end adapted to engage 25 said binding and to fit within said space in said closed condition, a tape carrying second fastener elements and disposed at and projecting beyond said reinforced end of said cover, said second fastener elements being engageable with said first fastener elements upon closing of said cover and being spaced from said upright walls, said outer layer including an extension flap overlying said binding, said reinforced end and said fastener elements and adapted for engagement with said ledge adjacent said upper margin of said side walls, and interfitting formations at said ledge and at said extension flap for effectuating said engagement.
